plugged or otherwise closed so that no mixture will pass it when closed.

5 Vaporized fuel passes from the recess 58 into the intake manifold, and is controlled by a valve 59 operated by a solenoid 60 disposed in a chamber formed in the body member.

10 Valve 59 is secured to or formed integral with the armature 62 of the solenoid, and is normally held unseated by an expansion coil spring 63 encircling the same, the spring being disposed between a collar 64 and the upper face of said solenoid.

15 Solenoid 60 is held in place by a plate 65 which also covers chamber 31, the cover having an opening 66 formed therein communicating with the float chamber in order to permit atmospheric pressure to react on the fluid therein during suction created by the engine.

20 Mixing tube 40, vaporizer 46, and the projecting portion of the armature are covered by a housing 68 which serves as an air cleaner and silencer to noise created by air passing through said mixing tube and vaporizer. To this end, the housing is provided with inner and outer perforated side walls 70 and 71 respectively between which is disposed a layer of metallic shavings or the like material 72, while the top or upper wall is internally lined with a layer 73 of sound absorbing material such as felt, cork, or the like.

25 30 The opposite ends of the winding or field of the solenoid are connected to conductors 74 and 75 leading therefrom to a switch 76, and a governor or circuit breaker 77 respectively. An incandescent lamp designated at L is interposed in conductor 74 to indicate to the operator of the vehicle whether the apparatus is functioning properly.

35 Referring to Figs. 3 and 4, the governor 77 consists of a cylindrical housing 78 in which is tiltably mounted a disk 79 provided with a pair of pins 80 having tapered points engaging recesses 81 formed in a closure plate 82.

40 Closure plate 82 is formed of insulating material, and is provided with an internal contact 83, and an external contact 84 connected by a conductor 85 embedded in said plate.

45 50 Disk 79 is normally held out of engagement with the internal contact 83 by a bow spring 86, the tension of which may be adjusted by a set screw 87. The governor serves to make and break the circuit through the solenoid, i. e., through engagement of the disk with the internal contact in a manner hereinafter described, and is adapted to be connected to a rotatable member of the engine, preferably to the shaft of the usual generator designated at G as shown in Fig. 1; the housing being provided with a socket 88 and set screw 89 for this purpose.

55 60 Referring to Fig. 7, the governor may be operated by the fan belt of the engine. In this instance, it is connected to a shaft 90 mounted in a bearing carried by a suitable support 91 adapted to be mounted on the cylinder block of the engine.

65 Conductor 75 is connected by a binding post to a spring contact 92, preferably mounted on the generator housing and engaging the external contact 84 of the governor.

70 75 Switch 76 consists of a rigid contact 93, and a spring contact 94 carried by a casing 95 secured to the dashboard or other suitable supporting member. The contacts are mounted on blocks of insulating material 96, and are provided with binding posts or the like 97, one of which is connected to a conductor 74, while the other is con-

nected to a conductor 98 leading to the storage battery B of the vehicle.

Secured to a rock shaft 99 is a cam 100 formed of insulating material, or is insulated from the shaft. The cam serves to close the contacts of the switch, and is actuated by the accelerator pedal through a series of links and levers arranged as follows:

80 85 Secured to shaft 99 is a lever 102 connected by a link 103 to one arm of a quadrant 104 pivotally mounted on a bracket 105 connected by a link 106 to the accelerator pedal. A link 107 is connected to the other arm of the quadrant, and an arm 108 secured to the shaft of throttle valve 13.

90 Assuming the vehicle is travelling at usual road speed, i. e., at or above 20 miles per hour, the contacts of the switch 76 will be opened due to depression of the accelerator pedal, while the contacts of the governor will be closed due to the disk 79 engaging the internal contact 83 by centrifugal force, and at the same time valve 59 will be unseated due to the circuit to the solenoid being broken by the switch.

95 100 However, should the throttle valve be closed while the vehicle is travelling at the speed above referred to, valve 59 will be seated and cut off the idling mixture due to closing of the circuit to the solenoid, and will remain seated as long as the vehicle travels at this speed, but will be unseated when the vehicle slows down to idling speed whereupon the flow of idling fuel will again be supplied. It will be noted that by adjusting the tension of the governor spring 86 by screw 87, the flow of idling fuel may be cut off at various speeds of the engine.

105 110 From the foregoing, it will be seen that the apparatus provides means whereby the idling fuel is supplied only when required thereby preventing unburnt gaseous fuel collecting in the cylinders and manifolds.

115 120 It will also be noted that should the circuit become permanently broken due to breakage of one of the conductors, etc., no stalling of the vehicle will result from lack of idling fuel as the valve 59 will then remain constantly opened.

I claim:

1. The combination with an internal combustion engine having an intake manifold, a carburetor provided with an accelerator throttle valve, and an accelerator pedal connected therewith, of a device for supplying idling fuel comprising a body member having a fluid conduit communicating with the intake manifold, a solenoid mounted in the body member, a valve connected to the armature of said solenoid, a spring normally holding said valve unseated, an electric switch, a cam interconnected with the accelerator pedal arranged to close the contacts of said switch when said accelerator pedal is in raised position, a governor rotatable in unison with the engine crank shaft, a conductor leading from a source of current to said switch, and conductors leading from the solenoid to said switch and to said governor respectively, said governor completing the circuit through said solenoid when the engine is rotating faster than idling speed, whereby upon closing of the accelerator throttle valve when the engine is rotating faster than idling speed, said valve will be seated and cut off the flow of idling fuel through the device until the engine slows down to idling speed, whereupon the circuit to said solenoid will be broken by said governor and the flow of idling fuel restored.

125 130 135 140 145 150 2. The combination with an internal combustion engine having an intake manifold, a car-

buretor provided with an accelerator throttle valve adapted to entirely close, and an accelerator pedal connected therewith, of a device for supplying idling fuel to the engine between said throttle valve and the intake valves comprising a body member, a solenoid mounted in the body member, a valve connected to the armature of said solenoid, means normally holding said valve unseated, an electric switch, a cam interconnected 10 with the accelerator pedal adapted to close the circuit to said solenoid when said accelerator

pedal is in raised position, and a governor provided with a tiltably mounted disk rotatable with the engine crank shaft, said governor completing the circuit through said solenoid upon closing of the throttle valve when the engine is rotating faster than idling speed, whereupon said valve will be seated and cut off the flow of idling fuel through the device until the engine returns to idling speed.

WILLIAM ROSS PULKINGHORN.
